RADIO SIGNALING APPARATUS

George W. Pettengill, Audubon, and Carleton D. Haigis, Camden, N. J., assignors to Radio Corporation of America, a corporation of Delaware

Application June 17, 1933, Serial No. 676,246

18 Claims. (Cl. 250—13)

Our invention relates to radio apparatus and particularly to combined transmitter and receiver apparatus for short wave transmission and reception.

5 A object of our invention is to provide a very small, readily portable, combined transmitter and receiver.

A further object of our invention is to provide an improved super-regenerative receiver for 10 short wave reception.

A still further object of our invention is to provide means for automatically compensating the tuning when switching from transmitter to receiver.

15 In practicing our invention, we provide a push-pull oscillator which has a tuned grid circuit and a tuned plate circuit, this oscillator including suitable electric discharge devices or electronic tubes so connected through switching circuits

20 that it may be utilized either as a transmitter oscillator or as the oscillating detector of a super-regenerative receiver. The antenna is coupled to the tuned plate circuit both when operating the oscillator for transmitting and when operating 25 it for receiving.

There is also provided in connection with the oscillator, an electric discharge or electronic tube amplifier, one tube of which may be utilized selectively as a speech amplifier or as an audio frequency oscillator for transmitter operation, and as an audio frequency amplifier for receiving 30 signals.

A second tube of the above amplifier may be utilized selectively as a modulator for the transmitting operation, and as a second audio frequency amplifier for receiving signals.

There are, furthermore, input and output circuits provided for the amplifier in which impedance devices are connected each having a plurality of functions, and the switching means for the oscillator is arranged to include means for controlling the functioning of the amplifier as above described, whereby the apparatus and electronic tubes required for a combined transmitter and receiver may be reduced to substantially a minimum, as is desirable in a portable signaling device.

Other features and advantages of our invention will appear from the following description taken 50 in connection with the accompanying drawings in which:—

Figure 1 is a circuit diagram of a combined transmitter and receiver constructed in accordance with one embodiment of our invention;

55 Figs. 2, 3, and 4 are circuit diagrams for the

apparatus shown in Fig. 1, for the three different switch positions;

Fig. 5 is a perspective view of the combined transmitter and receiver; and

Figs. 6 and 7 are views showing the switching mechanism for automatically compensating the tuning when switching from transmitting to receiving. 5

Referring to Fig. 1, the apparatus includes an oscillator which comprises two electric discharge 10 devices or electronic tubes 1 and 3, connected in push-pull relation to each other. These tubes may be of any suitable type such as the usual triode type shown, and are provided with a tuned grid circuit 5 which consists of an inductance coil 15 7 shunted by two variable condensers 9 and 11 connected in series. The ends of the inductance coil 7 are connected to the control-grids of the tubes 1 and 3, respectively.

The condensers 9 and 11 have rotor plates 20 which are mounted on a common shaft so that they are adjustable simultaneously. The rotor plates of condensers 9 and 11, and therefore the mid-point of the tuned grid circuit 5, are connected to the cathodes of the tubes 1 and 3 25 through suitable ground connections indicated in the drawings by the conventional symbol and the reference numeral 6.

The tubes 1 and 3 are provided with a tuned plate circuit 13 which comprises an inductance 30 coil 15 shunted by two variable condensers 17 and 19 connected in series. The ends of the inductance coil 15 are connected to the plates of the tubes 1 and 3, respectively.

The rotors of the condensers 17 and 19 also are 35 mounted on a common shaft so that they may be adjusted simultaneously, and these rotors also are connected to ground as indicated.

An antenna 21, such as a dipole antenna, is coupled to the tuned plate circuit 13 by means of 40 coils 23 placed in inductive relation to the plate inductance coil 15. The antenna 21 may be connected to the plate circuit 13 by capacitive coupling, if preferred. Particular attention is called to the fact that, in accordance with our invention, the antenna is always coupled to the plate circuit 13, whether the apparatus is being employed as a transmitter or as a receiver.

The push-pull oscillator is connected to electric discharge amplifier devices or electronic 50 tubes 25 and 27 in an audio frequency circuit to form either a super-regenerative receiver, a telephone transmitter, or a telegraph transmitter, depending upon the position of a switch 29 which is shown schematically in Fig. 1. 55

The switch 29, itself, is of conventional construction and includes four blocks 31, 33, 35, and 37 of insulating material, and a circular cam 39. When the cam 39 is in the central position shown in the drawings, the switch 29 is in its receiving position and the push-pull oscillator is connected to the audio frequency tubes 25 and 27 to form a super-regenerative receiver circuit. When the cam 39 is moved to the left, the blocks 31 and 35 are moved apart and the push-pull oscillator is so connected to the audio frequency tubes 25 and 27 that a telephone transmitter circuit employing Helsing modulation is formed. When the cam 39 is moved to the right, the blocks 33 and 37 are moved apart and a telegraph circuit employing Helsing modulation is formed.

Referring to Figs. 1 and 2, when the switch 29 is in the receiver position, the incoming modulated signal appears in the plate circuit 13 of the oscillator and is brought to the input circuit of an audio frequency amplifier comprising tubes 25 and 27 by means of a conductor 41 which connects the mid-point of the plate inductance coil 15 to the upper terminal of a primary winding 43 of an audio frequency transformer 45. In Fig. 1, this connection may be traced from the mid-point of the inductance coil 15 to the lower switch arm on the block 31, through a contact point and a continuation of conductor 41 to the lower switch arm on the block 33, through a contact point and a continuation of conductor 41 to the upper end of the primary winding 43.

The audio frequency circuit is completed from the upper end of winding 43 through the winding 35 to the positive terminal of the plate supply. The primary winding 43 is shunted by a condenser 47 having a capacity large enough to by-pass the greater part of the super-audible frequency current appearing in the output of the push-pull oscillator as a result of a super-regenerative quenching action hereinafter explained.

The grids of the oscillator tubes 1 and 3 are supplied with a biasing potential by means of a resistor 49 shunted by a condenser 51, the circuit through the resistor 53 being open when the switch 29 is in the receiving position. The grid biasing circuit may be traced from the mid-point of the grid inductance coil 7 through a resistor 55, the resistor 49 and a conductor 57 to the lower terminal of the secondary winding 59 of the audio frequency transformer 45, and from there to the negative or "—C" terminal of the source of biasing potential. In Fig. 1 the path of the conductor 57 may be traced from the lower terminal of the resistor 49 through the middle switch arm of the block 31 through a contact point and a continuation of conductor 57 to the middle switch arm of the block 33, through a continuation of conductor 57 to the lower terminal of the secondary winding 59.

The values of the grid biasing resistors 49 and 55 and shunting condenser 51 are made such that a negative potential will build up periodically on the grids of tubes 1 and 3 either to stop the oscillations or to reduce their intensity. This periodic quenching action occurs at a super-audible frequency which may be of the order of 30,000 cycles per second. In one embodiment of our invention, resistors 49 and 55 were given values of 25,000 ohms and 2000 ohms, respectively, and condenser 51 was given a value of .001 microfarad. In this same embodiment, resistor 53 was given a value of 5000 ohms.

It has been found that reception is materially improved by utilizing the resistor 55 in series

with the parallel connected units 49 and 51. This is believed to be for the reason that, with the circuit employed, the charging rate of the condenser is determined largely by the value of resistor 55 while its discharging rate is determined by the value of resistor 49.

The circuit above-described impresses the demodulated signal upon the input circuit of the vacuum tube 27. The plate of the tube 27 is connected to the positive or "+B" terminal of the 10 plate supply source through the primary 61 of an audio frequency transformer 63. The secondary 65 of the transformer 63 is shunted by a high resistance unit 67 and connected to the input electrodes of the amplifier tube 25. The plate of tube 25 is connected to the plate supply through an inductance coil 69 which forms the primary of an audio frequency transformer 71 when the apparatus is being used as a receiver.

The secondary 73 of transformer 71 is shunted 20 by a resistor 75 and the lower terminal connected to ground. In Fig. 1 the connection between the upper end of resistor 75 and the upper end of secondary 73 may be traced from resistor 75 through conductor 77, through a switch contact point and the lower switch arm of block 35, through conductor 79, the lower switch arm of block 37, a contact point, and through a conductor 81 to secondary 73.

A telephone receiver jack 83 is connected across 30 the resistor 75 by means of a connection to ground and a connection through a conductor 85 to a variable tap 87 on the resistor 75. By adjusting the variable tap 87, the output volume for telephone reception through the jack 83, may be 35 adjusted. The path of the conductor 85 may be traced from the receiver jack to a switch contact point and a switch arm 89 of the block 37, through a continuation of conductor 85, through a switch arm 91 of block 35, and through a contact point and a continuation of conductor 85 to the variable tap 87.

Although the scope of our invention is not to be restricted to any theory of operation advanced herein, it is our belief that the demodulation of the modulated carrier wave impressed upon the tuned plate circuit may be explained as follows: The modulated carrier is impressed upon the tuned grid circuit of the tubes 1 and 3 through the grid plate capacity of the tubes. 50 The system has negative resistance at least periodically and the signal builds up during these periods of negative resistance until it is of such amplitude that it is rectified by the tubes 1 and 3 functioning in parallel. The periodicity of the 55 negative resistance is introduced by the blocking action of the common grid condenser 51 and grid leak resistors 55 and 49 and is influenced by the plate circuit impedance.

At any rate the system behaves as though the 60 thermionic tubes 1 and 3 function in parallel to demodulate an incoming signal since the demodulated signal appears in the conductor 41 over which the plate potential is supplied to the tubes. It should be noted that as the oscillator 65 approaches the blocked condition, the grids of both tubes become more negative whereby the total plate current of the tubes decreases. This, of course, differs from the operation of push-pull amplifier circuits in which the grid of one tube 70 is made more positive at the same time that the grid of the other tube is made more negative whereby the output current remains substantially constant.

When the switch cam 39 is moved to the left

to connect the apparatus for operation as a telephone transmitter as shown in the simplified circuit of Fig. 3, the vacuum tube 27 still functions as an audio frequency amplifier. In this case, the microphone jack 93 is connected to the second primary winding 95 of the audio frequency transformer 45. The upper terminal of the primary winding 95 is connected to the center contact member 97 of the jack 93 through a connection which may be traced from the upper terminal of the primary winding through a conductor 99, the upper contact point and upper switch arm of the block 31, and through a continuation of the conductor 99 to the contact member 97 of the jack 93. The lower terminal of the primary winding 95 is connected to the ring contact member 101 of the jack 93 through a connection which may be traced from said lower terminal through conductors 103 and 105, a contact point and a switch arm 107 of the block 35, through a conductor 109 to the negative or "—C" bias supply terminal, and thence to ground since the positive side of the "C" bias supply source is grounded.

25 It will be noted that the connection to the upper terminal of the primary winding 43 has been broken at the bottom contact point and bottom switch arm of the block 31. Also, the resistor 75 is no longer in shunt across the secondary winding 73 since the circuit has been opened at the lower contact point and lower switch arm of the block 35. It will also be noted that the connection between the telephone receiver and the variable tap 87 has been broken by the opening of the circuit at the contact point and switch arm 91 of the block 35. Although no great amount of energy can now be supplied to the telephone jack 83, it is connected in series with the secondary winding 73 through a high resistance unit 111 so that the output of the transmitter may be monitored.

As mentioned above, the connection from the center point of the plate circuit inductance coil 15 to the input circuit of the audio frequency amplifier tube 27 has been broken. The mid-point of the inductance coil 15 is now connected to the upper end of the inductance coil 69, which now functions as an audio frequency choke coil in a Heising modulation circuit. This connection may be traced from the mid-point of the inductance coil 15 through the conductor 41, the lower switch arm of the block 31, a contact point 113, and through a conductor 115 to the upper terminal of the choke coil 69.

55 The quenching grid leak resistor 49 and grid condenser 51 are no longer in the oscillator circuit since the connection through the conductor 57 has been broken at the switch arm 115 of the block 31. The grids of the oscillator tubes 1 and 3 are now supplied with the proper bias for giving continuous sustained oscillations by means of a connection from the mid-point of the grid inductance coil 7 through the resistor 53 and through the upper contact point and upper switch arm of the block 35 to ground.

With the above described transmitter connections, it will be seen that the apparatus functions as a conventional transmitter having one audio-frequency amplifier stage, a modulator stage and a push-pull oscillator.

When the switch cam 39 is moved to the right, the connections are changed to make the transmitter function as a modulated continuous-wave telegraph transmitter as shown in the simplified diagram in Fig. 4. In this switch position, the

connections are the same as those described above for the telephone transmitter, except for the connections of the audio-frequency tube 27.

The lower primary winding 43 of the audio frequency transformer 45 is still disconnected from the transmitter circuit. The microphone jack 93 has been disconnected from the circuit since the connection through conductor 99 is broken at the upper contact point and upper switch arm of the block 31. The upper primary 10 winding 95 is now connected in a feed-back circuit in series with a transmitter key jack 117, so that the tube 27 is caused to oscillate at an audio frequency when the key circuit is closed. This feed-back circuit may be traced from the 15 plate of the tube 27 through a conductor 119, the upper contact point and upper switch arm of the block 33, through a condenser 121 and resistor 123 connected in series, through the primary winding 95, through a conductor 103, a 20 contact point and switch arm 125 of the block 31, and through conductor 127 to the center terminal of the key jack 117. The ring terminal of the key jack 117 is connected to ground so that when the key circuit is closed, the plate of 25 the tube 27 is connected to ground through the above-described circuit.

The telegraph circuit just described transmits a carrier wave which is modulated at the frequency of the audio frequency oscillator when 30 the key circuit is closed.

One important feature of our invention is the use of a compensating condenser 131 which is automatically connected into the circuit when the switch is thrown from the receiving position 35 to either one of the transmitting positions. We have found that when receiving fairly strong signals, it is necessary to tune the receiver oscillator to a frequency slightly different than the frequency of the incoming signal in order to 40 obtain best results. By connecting the small condenser 131 between one end of the grid inductance coil 7 and ground, when the switch 29 is thrown to a transmitting position, the apparatus is made to transmit at a slightly lower 45 frequency than the frequency at which it is tuned for receiving. Thus, by employing two similar transmitter-receiver units, the receiver will always oscillate at a slightly different frequency than the transmitter frequency. 50

It may be noted that the use of compensating condenser 131 is desirable, aside from the fact that the receiver should be tuned slightly off resonance, since the load on the oscillator is increased when the switch is thrown to the transmitting position. This increase in load tends to raise the frequency of the oscillator, but by switching in condenser 131 the frequency is actually lowered instead of being permitted to increase. 55

The mechanical details of the switching mechanism for the compensating condenser 131, as well as those of the rest of the transmitter-receiver, are shown in Figs. 5, 6, and 7.

Referring to Fig. 5, the complete transmitting 65 and receiving apparatus is enclosed in a casing 133 having an upper compartment and a lower compartment. The vacuum tubes and the push-pull oscillator tuning circuits are located in the upper compartment, while the rest of the apparatus, such as the audio frequency transformers and the switch 29, is located in the lower compartment. 70

The two push-pull oscillator tubes 1 and 3 are mounted between the grid circuit condensers 9 75

and 11 and the plate circuit condensers 17 and 19.

The stators of condensers 9 and 11 are supported by a block of insulating material 135, while the rotors of these condensers are mounted upon a hollow shaft 137. The inductance coil 7 is mounted on top of the insulating block 135.

The stators of condensers 17 and 19 are supported by an insulating block 139. The rotors of these condensers are mounted upon a shaft 141 which extends through the hollow shaft 137. The inductance coil 15 is mounted upon the insulating block 139, the coupling coil 23 being supported from insulating bushings 143 and held in inductive relation with the coil 15.

The audio frequency tubes 25 and 27 are mounted in the rear of the casing.

The rotors of condensers 9 and 11 may be turned by a knob 145 on a panel 147, the knob 20 being connected with the hollow shaft 137 through a friction drive. The position of the rotors of condensers 9 and 11 is indicated by the upper dial scale 149. The rotors of condensers 17 and 19 may be turned by the left hand knob 151 25 which is connected to the shaft 141 through a friction drive. The position of these rotors is indicated by the lower scale 153.

The panel 147 also carries a voltmeter 155, a filament current adjustment 157, a volume control adjustment 159, a power switch 161, and the handle 163 of the switch 29. Openings 164 in the lower left-hand corner of the panel are provided for plugging in devices such as a telephone receiver, a key, or a microphone for connection 30 with the jacks 83, 117 and 93, respectively, which are associated with said openings at the rear of the panel.

The compensating condenser 131 comprises metal plates 165 and 167 insulated from each 40 other and mounted upon an insulating support 169. Two arms 171 of conducting material, which are connected to the plate 165, extend from the insulating support 169. A conducting pin 173 extends from the switch 29 and is positioned between the conducting arms 171. When the switch 45 29 is in its receiving position, the pin 173 is out of contact with both arms. When switch 29 is thrown to one transmitting position, it makes contact with one arm 171 and when thrown to 50 the other transmitting position, it makes contact with the other arm 171. The compensating condenser 131 is connected into the oscillator circuit through the pin 173 as described, since this condenser is in the radio frequency 55 circuit and therefore could not satisfactorily be switched in and out of the circuit through the contacts on the switch 29.

The manner in which the pin 173 is operated by means of the switch 29 is shown in Figs. 6 60 and 7. The switch, itself, is of conventional construction and comprises a supporting member 175, which has the handle 163 and cam 39 mounted thereon at one end. The insulating blocks 31, 33, 35, and 37 through which the switch arms 65 are moved, are mounted upon the spring members 177 with which the cam 39 makes contact. In order to simplify the drawings, the switch arms actuated by the insulating blocks have not been illustrated in Figs. 6 and 7.

70 A lever 179 is pivotally mounted upon the switch supporting member 175. The pin 173 extends upwardly from one end of lever 179. The other end of the lever 179 is in the form of a yoke 181, the arms of which extend on each side of the cam 39. Pins 193 extend downwardly from the ends

of the yoke arms so that they are opposite the cam 39. Thus, when the cam 39 is moved to either one of the transmitting positions, the cam 39 comes into contact with one of the pins 183 and the pin 173 is moved into contact with one of the conducting arms 171 extending from the compensating switch 131 to complete a connection from the condenser plate 165 to ground. This connects the compensating condenser 131 in parallel with condenser 11 as indicated in Fig. 1.

If desired, the condenser 131 may be replaced by an inductance coil coupled to coil 7, said inductance coil being short circuited by pin 173 when the apparatus is in the receiving position 15 and open-circuited when in the transmitting position. By varying the amount of coupling between this coil and coil 7, it is possible to secure the proper degree of compensation.

In the operation of the system described, the inductance 15 in the anode circuit of the oscillator devices 1 and 3 serves to transmit signals to the antenna system through suitable coupling means, and for incoming signals, serves as a coupling means together with the internal inner-electrode 25 capacity of the devices 1 and 3 for the input or grid circuit in which the inductance 7 is included.

The devices 1 and 3 are in continuous oscillation at frequencies determined by the tuning condensers associated with the inductances 7 and 15, 30 and as has hereinbefore been explained, the devices 1 and 3 operate as oscillators for signal transmission or as oscillating super-regenerative detectors for receiving signals.

The device 27 may operate as a speech amplifier for phone operation, in connection with a microphone or other suitable voice input device, not shown, when connected with the phone jack 23 and the primary winding 95, which is of low impedance. The winding 95 is also utilized for 40 feed-back purposes for interrupted continuous telegraph wave transmission in connection with the plate lead 119, whereby the device 27 may operate as an audio frequency oscillator.

In the receiving position of the switch 29, the device 27, furthermore, operates as a first audio frequency amplifier. Therefore, it has three separate functions in the system described. The triple function obtainable in connection with the device 27 is due in part to the use in the input 45 transformer 45 of a low impedance feed-back and microphone input winding 95, a high impedance input winding 43 for audio frequency signals, and a bypass condenser 47, the latter providing a shunt path for the quenching frequency employed for 55 super-regeneration.

The device 25 may function as a modulator for transmitter operation, or as the second audio frequency or output amplifier device for signal reception. The dual function of this device is in 60 part, made possible by the use of a suitable output transformer 71 which also may serve a dual purpose, as modulation choke coil for signal transmission and as an output transformer for signal reception, as hereinbefore described. The primary winding 69 serves as the modulation choke winding and as such supplies anode current to the device 25 and the devices 1 and 3 for phone operation, through the lead 115.

In connection with Fig. 5 it may be pointed out 70 that the tuning condensers are arranged in ganged relation with the inductances mounted directly thereon and above the condensers, making it possible to provide short leads to the output terminals at the top of the apparatus, while the wiring and

other circuit elements are carried by the base to which the panel is secured.

The oscillator tubes are mounted between the tuning units, each unit comprising a pair of tuning condensers and the self supporting inductance, whereby the leads to the tubes are relatively short, as is desirable in high frequency apparatus. The tubes are, furthermore, easily removable and replaceable in the sockets, since they are by this construction, permitted to be mounted in a vertical position above the base-board. All of the control apparatus, including the meter, jacks and switches, are mounted on and supported by the front panel. The apparatus as a complete unit may therefore, be inserted in a suitable casing when in use and may easily be removed therefrom for inspection and adjustment.

Because of the amplified circuits and reduction in the number of electrical discharge devices or electron tubes required, the apparatus may be made in a highly compact form as is indicated in the drawings, while, at the same time, the inductance windings are suitably spaced from the shielded side walls of the casing in which the apparatus is mounted in use.

From the foregoing description it will be apparent that various modifications may be made in our invention without departing from the spirit and scope thereof, and we desire, therefore, that only such limitations shall be placed thereon as are necessitated by the prior art and as set forth by the appended claims.

We claim as our invention:

1. The method of intelligence reception and transmission by the use of a plurality of electronic tubes disposed in balanced relation and having common grid and plate circuits, which includes causing said tubes to generate oscillations at a frequency of the order of that of the desired signal, causing the amplitude of said oscillations to be limited periodically, impressing a signal wave upon said plate circuit to further modify said oscillations, and de-modulating said modified oscillations by said tubes to produce audible signal indications in said plate circuit, and later utilizing said tubes for transmitting a carrier wave.

2. The method of intelligence reception and transmission through the use of a plurality of electronic tubes disposed in balanced relation and having common grid and plate circuits, which includes causing said tubes to generate oscillations, impressing signal waves upon said plate circuit, selectively causing said oscillations to be interrupted at a predetermined rate to receive said signal waves, and impressing upon said plate circuit a modulation signal without interrupting said oscillations, for transmitting corresponding signal waves.

3. The method of selective intelligence transmission and reception through the use of a balanced electric discharge oscillator and an electric discharge amplifier, which includes selectively and for one condition of operation, causing said oscillator to operate as a signal detector with the oscillations periodically suppressed, applying the demodulated signal output therefrom to said amplifier and receiving the amplified output from said amplifier, for a second condition of operation, causing said oscillator to operate freely at a predetermined frequency, transferring said oscillations as signal energy to a utilization circuit, and supplying modulation signals to said oscillator through said amplifier, and for a third condition of operation, additionally providing signal regeneration in said amplifier and key controlling the

regeneration to provide interrupted continuous wave signals.

4. A combined radio transmitter and receiver comprising, in combination, a balanced electric discharge oscillator having tapped grid and anode circuit inductances, an audio frequency amplifier having an input coupling means and an output coupling means, and switching means for selectively connecting a tap on the grid inductance to biasing potential supply circuits, one of which includes an impedance and a capacitor connected in parallel, and for connecting a tap on the anode inductance selectively to the input and to the output coupling means for said amplifier.

5. A combined radio transmitter and receiver comprising in combination, a balanced electric discharge oscillator having tapped grid and anode circuit inductances, an audio frequency amplifier having an input coupling means and an output coupling means, switching means for selectively connecting a tap on the grid inductance to the oscillator cathode directly and through a source of biasing potential including an impedance and a capacitor connected in parallel, and for connecting a tap on the anode inductance selectively to the input and the output coupling means for said amplifier, and means providing audio frequency regeneration through said amplifier input coupling means.

6. In a radio signaling system, the combination of a balanced electric discharge oscillator having an output anode circuit, and an electric discharge amplifier having an input circuit and an output anode circuit, and switching means interposed between said oscillator and said amplifier for connecting the output anode circuit of the oscillator selectively with the input circuit and with the output circuit of the amplifier.

7. In a radio signaling system, the combination of a balanced electric discharge oscillator having an output anode circuit, and an electric discharge amplifier having an input circuit and an output anode circuit, switching means interposed between said oscillator and said amplifier for connecting the output anode circuit of the oscillator selectively with the input circuit and with the output circuit of the amplifier, means for causing regeneration in said amplifier, and a circuit for controlling the regeneration arranged to be connected therewith when said output circuits are connected together.

8. In a radio signaling system, the combination of a balanced electric discharge oscillator having an output anode circuit, and an electric discharge amplifier having an input circuit and an output anode circuit, and switching means interposed between said oscillator and said amplifier for connecting the output anode circuit of the oscillator selectively with the input circuit and with the output circuit of the amplifier, said amplifier being adapted to transmit signals in the audio frequency range and having an input transformer provided with a relatively high impedance input winding and a relatively low impedance input winding, and having an output transformer providing a modulation choke coil common to both output circuits when said switching means is in a predetermined position.

9. In a radio signaling system, the combination of a balanced electric discharge oscillator having an output anode circuit, and an electric discharge amplifier having an input circuit and an output anode circuit, switching means interposed between said oscillator and said amplifier for connecting the output anode circuit of the

- oscillator selectively with the input circuit and with the output circuit of the amplifier, said amplifier being adapted to transmit signals in the audio frequency range and having an input trans-
5 former provided with a relatively high impedance input winding and a relatively low impedance input winding, and having an output transformer providing a modulation choke coil common to both output circuits when said switching means is in
10 a predetermined position, means connected across said high impedance winding for bypassing a super-regenerative quenching signal, and means controlled by said switching means for changing the operating frequency of said oscillator.
- 15 10. In combination, a super-regenerative receiver comprising a plurality of electronic tubes connected in balanced relation and having a common tuned grid circuit and a common tuned plate circuit whereby said tubes may jointly be operated
20 as an oscillating detector, means for altering the magnitude of said oscillations at a superaudible rate, means for impressing radio-frequency signals upon said tuned plate circuit, means for transferring audio-frequency signals from said
25 tuned plate circuit, and means for jointly utilizing said tubes as the oscillator of a transmitter.
11. In combination, a super-regenerative receiver comprising a pair of electric discharge devices connected in push-pull, said devices having
30 tuned grid circuits and tuned plate circuits whereby said devices may operate as an oscillating detector, means for decreasing the intensity of said oscillations periodically at a superaudible rate, means for impressing a signal modulated radio-
35 frequency carrier wave upon said plate circuits, whereby said carrier wave is demodulated to produce signals in said plate circuit, means for transferring said signals from said plate circuits, and means for utilizing said tube as the oscillator of
40 a transmitter.
12. In combination, a super-regenerative receiver comprising a pair of electric discharge devices connected in balanced relation, means including a tuned grid circuit for said tubes and a
45 tuned plate circuit for making said devices operate as an oscillating detector, means for decreasing the intensity of said oscillations periodically at a superaudible rate, a radio-frequency signal circuit, means for coupling said signal circuit to said
50 tuned plate circuit, a translating device, means for connecting said translating device to said plate circuit for receiving audio signals, and means for utilizing said tubes as the oscillator of a transmitter.
- 55 13. In combination, a signal receiving apparatus comprising a plurality of electronic tubes disposed in balanced relation and having a common tunable grid circuit and a common tunable plate circuit, means enabling said tubes to generate
60 oscillations, means for impressing a modulated signal wave directly upon the plate circuit of said tubes in balanced relation, means for providing a discontinuous grid leakage from said tubes, means
for transferring audio frequency signals from said plate circuit, and means for utilizing said tubes as the oscillator of a transmitter.
14. In combination, a signal receiving apparatus comprising a plurality of electronic tubes disposed in balanced relation and having a common tunable grid circuit and a common tunable plate circuit, means enabling said tubes to generate oscillations, means for impressing a modulated signal wave directly upon the plate circuit of said tubes in balanced relation, means for providing a discontinuous grid leak from said tubes, said last means including a resistor shunted by a condenser and a resistor connected in series with said shunted resistor, means for transferring audio-
10 frequency signals from said plate circuit, and means for utilizing said tubes as the oscillator of a transmitter.
15. In combination, an oscillator comprising a pair of electronic tubes connected in balanced relation to oscillate at a high frequency, said tubes having a tuned grid circuit and a tuned plate circuit, an antenna, means for coupling said antenna to said plate circuit, a modulating circuit, a receiver circuit, means for selectively connecting said modulating circuit and said receiver circuit with said plate circuit, and means for decreasing the intensity of said oscillations periodically at a superaudible rate when said receiver circuit is connected to said plate circuit.
20
16. In combination, an oscillator having a grid circuit and a plate circuit, an antenna coupled to said plate circuit, an electric discharge amplifier device having an input circuit and an output circuit, an audio-frequency transformer in said output circuit, switching means having a receiving position and a transmitting position, circuit means for coupling said plate circuit to said input circuit and for establishing a telephone receiver connection with the secondary of said transformer when said switching mechanism is in said receiving position, and circuit means for establishing a connection between said plate circuit and the primary of said audio-frequency transformer when said switching mechanism is in said transmitting position.
30
17. In combination, an oscillator, a modulating circuit, a receiver circuit, switching means for selectively connecting said circuits to said oscillator, and means for changing the frequency of operation of said oscillator in response to the operation of said switching means.
40
18. In combination, an oscillator, a modulating circuit, a receiving circuit, switching means for selectively connecting said circuits to said oscillator, means for causing the oscillations of said oscillator to be reduced in intensity periodically at a superaudible frequency when said receiving circuit is connected to said oscillator, and means for changing the tuning of said oscillator in response to the operation of said switching means.
